PAUL MACGAHAN, OF ORANGE, NEW JERSEY, ASSIGNOR TO WESTINGHOUSE ELECTRIC & MANUFACTURING COMPANY, A CORPORATION OF PENNSYLVANIA.

INSTRUMENT STRUCTURE.

Application filed July 17, 1926. Serial No. 123,204.

My invention relates to instrument structures and particularly to means for supporting the movable elements of indicating meters of the D'arsonval type.

5 One object of my invention is to provide means, of the above indicated character, that shall reduce the likelihood of damage to the instrument from shocks and jars.

Another object of my invention is to increase the surface-creepage distance between 10 parts of unlike potential in D'arsonval instruments.

Another object of my invention is to reduce the number of parts usually required 15 in instruments of the above-indicated character to thereby effect economy of construction and to facilitate the assembly of the instruments.

A further object of my invention is to 20 provide a D'arsonval instrument that shall be simple and durable in construction and effective in operation.

In D'arsonval instruments of a certain construction, it has heretofore been usual 25 to support the movable coils or elements between the poles of permanent magnets by means of metal bridge members that are supported, adjacent to the ends thereof, by metal standards from which the bridges are 30 insulated by small insulating washers or bushings.

These small parts are not only difficult to handle in assembling the instruments but also afford only a relatively small surface 35 creepage distance between the bridges and standards.

I propose to overcome the above-mentioned objections and to provide a materially improved instrument of fewer parts, 40 more economical construction, better insulating characteristics, easier assembly and more effective operation and one which is less likely to be damaged by rough usage.

Accordingly, in practicing my invention, 45 I so construct the bridge member or members entirely of insulating material as to permit them to severally take the places of two or more small parts heretofore used and to provide the other advantages above-mentioned.

Figure 1 of the accompanying drawings, 50 is a side elevational view of a portion of a

D'arsonval instrument embodying my invention, and

Fig. 2 is a bottom plan view of the instrument shown in Fig. 1.

The device comprises, in general, a permanent field magnet 1, pole members 2 therefor, a stationary cylindrical core member 3 disposed between the pole members 2, 60 a movable element or coil 5 surrounding the core member 3, a pointer 6 carried by the coil 5, non-magnetic bridge members 7 secured to the magnet 1 by bolts 8 for supporting the stationary core 3, insulating 65 bridge members 10 carrying bearing members 11 for the coil 5, and standards 12 for supporting the bridge members 10.

The permanent magnet 1 is preferably of inverted U-shape and of rectangular cross 70 sectional area having plane inner surfaces against which corresponding surfaces on the pole members 2 rest. The pole members 2, which are suitably secured in position between the free ends of the magnet 1, are 75 provided with inner or pole surfaces of cylindrical curvature and of sufficiently greater radius than the cylindrical core 3 to provide cylindrical spaces in which the sides of the coil 5 are adapted to turn.

The core 3 is supported, adjacent to its ends, by the non-magnetic bridge members 7 in a specific manner not germane to this invention, and the latter are provided with arcuate slots 14, registering with the spaces 85 between the core 3 and pole members 2, through which portions of the coil 5 extend.

The coil 5 is wound on a bobbin or frame 15 which carries pointed trunnions 16 to be supported by the bearing members 11. The latter, which are in the form of screws having cupped inner ends for cooperation with the ends of the trunnions 16, are supported in the insulating bridge members 10 and held in position by nuts 17.

The standards 12 are of any suitable construction and may consist of metal sleeves through which screws 18 extend. The latter, which also serve to mount the insulating bridges 10, may further extend into the pole 100 members 2.

The bridge members 10 are preferably constructed as punchings of relatively thin sheet micarta or other suitable insulating

material having enlarged apertured discoidal end portions for the reception of the screws 18 and similar central portions for the reception of the bearing screws 11.

5 In a usual instrument of this character, in which the bridge members 10 are of metal, it is necessary to provide insulation between the bridges and the screws 18. This insulation, adjacent to each screw, may be in the 10 form of a washer and a flanged bushing, a sleeve and two washers or may be otherwise constructed.

Whatever may be the manner of so providing this insulation, it involves small parts 15 which are difficult to handle, which provide very little surface-creepage distance between the bridge and the standards, and which are relatively expensive, as compared to the device of my invention.

20 Being of insulating material, the bridge members 10 are of a damped yieldable nature which cushion the forces of shocks and jars to the instrument and thereby prevent damage to the delicate moving parts and 25 bearings.

While I have shown and described a particular form of my invention, changes may be effected therein without departing from the spirit and scope thereof, as indicated by the appended claims.

30 I claim as my invention:

1. In an instrument, the combination with a field-magnet structure embodying spaced 35 cooperating pole portions and a movable element disposed between said portions, of bridge structure of insulating material extending transversely to the axis of said element for supporting the same in position.

2. In an instrument, the combination with a field-magnet structure embodying spaced 40 cooperating pole portions and a movable element disposed between said portions, of bridge structure of insulating material extending transversely to the axis of said element for supporting the same in position,

said bridge structure being mounted adjacent to its ends on said field-magnet structure.

3. In an instrument, the combination with a field-magnet structure embodying spaced 50 cooperating pole portions and a movable element disposed between said portions, of bridge structure of insulating material extending transversely to the axis of said element for supporting the same in position, 55 and portions extending from said field-magnet structure substantially parallel to said axis adjacent to the ends of said bridge for supporting the same.

4. In an instrument, the combination with 60 a field-magnet structure embodying spaced cooperating pole portions and a movable element disposed between said portions, of a bridge member of insulating material extending transversely to the axis of said element adjacent to each end thereof for supporting the same in position, and portions 65 extending from said field-magnet structure substantially parallel to said axis adjacent to the ends of the bridge members for supporting the same.

5. The combination with a deflecting system comprising magnetic-flux-controlled structure, of members of insulating material disposed transversely of said structure and 75 on which said deflecting system is pivoted, and means for supporting said insulating members in spaced relation.

6. The combination with a deflecting system comprising magnetic-flux-controlled 80 structure, of members of phenol condensation material disposed transversely of said structure and on which said deflecting system is pivoted, and means for supporting said members in spaced relation.

85 In testimony whereof, I have hereunto subscribed my name this 8th day of July, 1926.

PAUL MacGAHAN.
